UNITED STATES PATENT OFFICE.

FRANCIS W. COOPER AND WILLIAM H. YAWGER, OF MONTREAL, QUEBEC, CANADA;
SAID YAWGER ASSIGNOR TO SAID COOPER.

RAIL-ANCHOR.

1,276,178.

Specification of Letters Patent. Patented Aug. 20, 1918.

Application filed February 12, 1918. Serial No. 216,748.

To all whom it may concern:

Be it known that we, FRANCIS W. COOPER and WILLIAM H. YAWGER, respectively a subject of the King of Great Britain and a citizen of the United States, and residents of the city of Montreal, in the Province of Quebec and Dominion of Canada, have invented certain new and useful Improvements in Rail-Anchors, of which the following is a full, clear, and exact description.

This invention relates to improvements in rail anchors, and the object is to provide a rail anchor of simple and durable construction which will be very efficient in operation and which will not be dislodged or loosened by vibration in the rail.

The device consists of two parts, one of which is preferably in the form of a malleable casting adapted to be applied to the base of a rail and provided with a downwardly projecting offset portion adapted to bear against the side of a tie. The other part is a key, preferably of spring steel, which secures the anchor to the rail.

In the drawings which illustrate the invention;—

Figure 1 is a front elevation of the anchor as applied to a rail.

Fig. 2 is a rear elevation.

Figs. 3 and 4 are elevations of the large and small ends of the anchor respectively.

Fig. 5 is a plan view of the anchor with the key removed.

Fig. 6 is an elevation of the key.

Figs. 7 and 8 are sections on the lines 7—7 and 8—8 respectively of Fig. 2.

Referring more particularly to the drawings, 11 indicates the base of a rail to which the anchor is applied and 12 the tie supporting the rail. The anchor proper comprises a pair of parallel plates 13, connected by a top plate 14 and end webs 15 and also at the center by webs 16. The top plate is inclined with relation to the rail base, as clearly shown and at the upper or small end of the device, the side plates 13 curve around the edge of the rail base so as to form hooks 17. At the lower or large end of the anchor, the side plates curve over the rail base and form hooks 18. The top plate 14 and end webs 15 unite and connect the hook portions 17 and 18 of the side plates at their inner or lower edges. The hooks 17 and 18 form with the top plate a recess which is larger at the bottom than at the top. The length of this

recess at the bottom is equal to the width of the rail base plus the overhang of the hooks 17. It will also be seen that the overhang of the hook 18 is twice that of the hook 17 and that the lower edge of the hook is stepped, each step conforming with the curvature at the edge of the rail base. The lower step 19 of these two is used only when applying the anchor to a rail and is produced by the extension of the recess to permit the anchor to be moved transversely of the rail a sufficient distance for the hook 17 to swing clear of the rail edge. The second step 20 corresponds with the hooks 17 and bears on the edge of the rail when the anchor is in place. It is in order to provide sufficient shoulder between the steps 19 and 20 to hold the anchor against transverse movement on the rail and also to enable the upper step 20 to conform exactly to the rail edge, that the top plate 20 is inclined as shown. The structure is thus provided with a hook portion at each end, adapted to embrace the edges of a rail base and hold the anchor against transverse movement, and with a recess under one of the hooks permitting movement of the anchor transversely of the rail, so that the hook at the opposite end will clear the rail.

A pair of plates 21 are provided in rear of the back plate 13 and extend parallel therewith and in line with one another. These plates 21 are connected to the back plate 14 at their lower edges and at their outer extremities by webs 22 arranged in the plane of the webs 15, and also at their inner extremities by the webs 16, which extend beyond the plane of the plates so as to brace them. This arrangement provides a deep, narrow groove tapering from the large end of the anchor to the small end and open or interrupted between the webs 16, which, as will be clearly seen, are located approximately centrally under the rail. Openings 23 are provided in the webs 22 to give access to the groove at the ends. As will be clearly seen, the deep end of the groove is at the large end of the anchor. At the small end of the anchor, a projection 24 is provided on the back plate 13 by which the floor of the groove is continued beyond the web 22. A projection 25 is also provided on the small end of the back plate 13 beyond the web 22, which has an inclined surface leading away from the side wall of the groove.

A key 26 is provided for insertion in the groove and is tapered in accordance with the relative inclination of the groove floor and rail base. This key is preferably of 5 spring steel and made with a slight curve or camber, as clearly shown in Fig. 6, so that when inserted in the groove, it will bear adjacent its extremities on the floor of the groove and at its center against the rail base. 10 When the key is forced home, it will be straightened out and will thus be held at all times by its own spring action against loosening by vibration in the rail. To facilitate driving of the key, the lower edge thereof is 15 sharply tapered at the small end, as at 27, and for the same reason, the floor of the groove between the small end of the anchor and the adjacent web 16 is more sharply inclined for a distance as indicated at 28. The 20 inner face of the plate 21^a is also curved away from the back plate 13, where it joins the web 16, so as to lead the key into the small end of the groove. It will be understood that the invention is not limited to a 25 spring steel key, nor to a curved key, as a curved key of ordinary steel or a key without camber may be used.

The front plate 13 is provided between the webs 16 with an offset portion 29 inclined 30 relatively to the vertical and projecting a considerable distance below the lower edge of the plate. The lower portion 30 of this offset is formed parallel with the plate 13. The entire offset is supported by the webs 16, 35 which it will be seen connect with both the front and back plates and curve around the key holding plates 21.

The operation of the device is extremely simple. To apply the device to a rail, the 40 large end of the anchor is hooked over one edge of the rail base as far as it will go and the hook 17 at the small end swung clear of the other edge of the rail base. The anchor is then moved transversely of the rail, so as 45 to engage the hook 17 over the rail base and cause the step 19 at the large end to disengage the rail and the step 20 to engage with it. The anchor is now held against transverse movement. The key is inserted in the 50 slot and driven tight. If a curved key is used, it becomes straightened out in the driving and holds itself in place against loosening by vibration in the rail. If a straight tapered key is used, it holds tight 55 by wedging between the floor of the groove and the base of the rail. In the final part of the driving, the tip of the key as it passes the web 22 at the small end of the anchor runs out over the inclined surface of the projection 25, and is thereby bent in exactly the same manner as a nail is clenched. This bending further serves to hold the key against loosening.

It will of course be understood that in 60 placing the anchor, it is located with the de-

pending portion 30 in close contact with the side of a tie. If the rail tends to move longitudinally or "creep", the thrust of the depending portion 30 against the tie tends to prevent this. As soon as this depending 70 portion is subjected to a thrust, it tends to rotate the anchor about its longitudinal axis, forcing the front edge of the hooks 17 and 18 down tightly on the rail and forcing the key up against the bottom of the rail. In 75 this upward thrust of the key, the force is transmitted from the part 30 through the webs 16 direct to the key and not through the front plate. If the thrust is sufficient to cause the portion 30 to be embedded in the 80 tie, the inclined portion 29 bearing against the tie tends further to draw the anchor down tightly on the rail.

Having thus described our invention, 85 what we claim is:—

1. A rail anchor comprising a body having the ends hooked to engage the edges of the rail base, a wedge slideable in a groove offset from the main part of the body member and running transversely of the rail, the wedge being in a different transverse vertical plane from that of the hooked body ends in close engagement with the edges of the rail base. 90

2. A rail anchor comprising a body hooked at the ends to engage the edges of a rail base, a depending offset portion at one side of said body adapted to engage a tie, and a wedge at the opposite side of the body adapted to engage a rail base and hold the anchor rigid thereon. 95

3. In a device according to claim 2, webs positioned to transmit thrust against the depending portion directly to the key. 105

4. In a rail anchor, a rigid body hooked at its ends to engage the edges of a rail base and having a recess at one end for the reception of a rail edge, whereby the anchor may be moved transversely on a rail to clear the hook at the opposite end from the rail edge, a shoulder above the recess holding the anchor against movement transversely of the rail when in normal position, and a wedge insertible in the body transversely of the rail adapted to hold the hooks and shoulder in close engagement with the edges of a rail base. 110

5. In a rail anchor, a body hooked for engagement with a rail, and a resilient wedge slideable in the body and engageable transversely with a rail on which the body is fixed to hold the body, said wedge being held against loosening due to vibration by its resiliency. 115

6. In a rail anchor, a body hooked for engagement with a rail, and a longitudinally curved wedge of spring material adapted to be inserted between the body and rail longitudinally of the anchor and transversely of the rail, whereby said wedge will be 120 125 130

straightened and will hold against loosening due to vibration.

7. In a rail anchor, the combination with a rail of an anchor body engaging the rail, and a normally curved resilient wedge driven between the body and rail transversely of the rail whereby said wedge tends to be straightened.

8. In a rail anchor, a body, adapted for engagement with a rail, having a groove therein, a key insertible in said groove transversely of the rail to clamp the body to the rail, and a projection on the body having an inclined surface disposed to deflect the leading end of the key, whereby said key is held against loosening by vibration.

9. In a rail anchor, a body adapted for engagement with a rail, a key-way in said body comprising a pair of aligned grooves separated adjacent the center of the body, whereby a key in said key-way is unsupported in its central portion.

10. In a rail anchor, a body adapted for engagement with a rail, a pair of aligned laterally projecting flanges at the bottom of the body, forming a key seat, a wall adapted to retain a key on said seat, and supporting webs for said seat and wall.

11. A rail anchor according to claim 10, having portions of said key seat and key retaining wall inclined relatively to the remainder, whereby a key will be guided into a predetermined path.

12. In a rail anchor, a body comprising a pair of parallel plates hooked at the ends for engagement with a rail base, a top plate connecting said side plates, webs connecting the side plates adjacent the ends thereof, and in the hooked portions, a depending offset portion on one of said side plates, a key retaining means on the other of said side plates, and common supporting webs

for the offset portion and the key retaining means.

13. A device according to claim 12, having a recess at one end for the reception of a rail base, whereby the anchor may be moved transversely of a rail to engage or disengage the hook at the opposite end relatively to the rail.

14. A device according to claim 12, in which the top plate is inclined relatively to a rail base, whereby the anchor may be tilted relatively to a rail for application and removal.

15. A device according to claim 12, in which the key retaining means is arranged to support the key toward its ends only.

16. A device according to claim 12, in which the entrance end of the key retaining means is flared to guide a key.

17. A device according to claim 12, in which a projection is provided having an inclined surface adapted to deflect the leading end of a key.

18. A rail anchor comprising a body having hooks suspending the body from the rail, and a depending portion centrally disposed with respect to the rail adapted to receive thrusts parallel with the rail, and separate means on the opposite side of the anchor from said depending portion engaging the rail base, whereby said thrusts operate to secure the anchor more firmly to the rail.

19. In a rail anchor, a body adapted for engagement with a rail, a key way in said body including a key seat arranged to support the key at each side of an intermediate portion and to leave said intermediate portion unsupported.

In witness whereof we have hereunto set our hands.

FRANCIS W. COOPER.
WILLIAM H. YAWGER.
